(57) **CLAIM**

The ornamental design for a motor vehicle and/or toy replica thereof, as shown and described.

DESCRIPTION

FIG. 1 is a rear perspective photographic view of a motor vehicle and/or toy replica showing my new design;

FIG. 2 is a right side perspective photographic view with the unshown left side perspective photographic view being a mirror image thereof;

FIG. 3 is a top/front perspective photographic view thereof;

FIG. 4 is a front perspective photographic view thereof;

FIG. 5 is a front/right perspective photographic view thereof;

FIG. 6 is a top/front/right perspective photographic view thereof;

FIG. 7 is a top/rear/right perspective photographic view thereof;

FIG. 8 is a top/front perspective photographic view thereof;

FIG. 9 is a top/right perspective photographic view with the unshown top/left perspective view being a mirror image thereof;

FIG. 10 is a rear perspective photographic view of a motor vehicle and/or toy replica showing an alternative embodiment of my new design;

FIG. 11 is a right side perspective photographic view with the unshown left side perspective view being a mirror image thereof;

FIG. 12 is a top/front perspective photographic view thereof;

FIG. 13 is a front photographic view thereof;

FIG. 14 is a front/right perspective photographic view thereof;

FIG. 15 is a top/front/right perspective photographic view thereof;

FIG. 16 is a top/rear/right perspective photographic view thereof;

FIG. 17 is a top/front perspective photographic view thereof; and,

FIG. 18 is a top/right perspective photographic view with the unshown top/left perspective view being a mirror image thereof.
